Specification for Design.

Patented Mar. 28, 1922.

Application filed November 21, 1921. Serial No. 516,881. Term of patent 14 years. ✓

To all whom it may concern:

Be it known that I, LOUIS SIDERMAN, a citizen of the United States, residing at Detroit, in the county of Wayne and State of Michigan, have invented a new, original, and ornamental Design for Stockings, of which the following is a specification, reference being had to the accompanying drawing, forming part thereof.

The figure is a perspective view of a pair of stockings, illustrating the design feature of the heel portion in side and rear elevation.

I claim:

The ornamental design for a stocking, as shown.

LOUIS SIDERMAN.
